UNITED STATES PATENT OFFICE.

JOHN COYNE, OF PITTSBURG, PENNSYLVANIA.

NAIL-CUTTING MACHINE.

SPECIFICATION forming part of Letters Patent No. 250,346, dated December 6, 1881.

Application filed December 16, 1880. (No model.)

To all whom it may concern:

Be it known that I, JOHN COYNE, of Pittsburgh, in the county of Allegheny and State of Pennsylvania, have invented a new and useful Improvement in Nail-Cutting Machines; and I do hereby declare the following to be a full, clear, and exact description thereof.

My invention relates to the improvement of that class of nail-cutting machines commonly known to the trade as the "Reed" or "American" machine, in which the heading-lever is actuated by the cutting-lever; and it consists in certain modifications and improvements of the several parts of the machine.

The machine in common use for cutting nails has remained substantially unchanged for the past seventy years, and it is the object of my invention to remedy certain defects in its construction and operation.

For greater clearness I will take up these various points *seriatim*, describing the prior construction of each detail and its faults, and then describe my improved construction, whereby I remedy the defect. In this way the construction and operation of my improved machine will be fully described.

In the drawings, (six sheets,) Figures 1 and 2 are perspective views of my improved machine. Fig. 3 is a view of the three operative levers, illustrating their relative positions in the machine. Fig. 4 is a view of the transverse arms of the gripping-lever, partly in section, to show the construction of one of the center bushings and its lubricating ports. Fig. 5 is a side view of the heading-lever, showing the attachment of the heading-die. Fig. 6 is a view illustrating the application to my improved machine of a self-feeder actuating attachment. Fig. 7 is a sectional view, showing the connection of the pitman to the crank-pin of the long arm of the cutting-lever. Fig. 8 is a perspective view, showing the attachment of the nail-selector. Figs. 9 and 10 are sectional views of the friction-plates and their sockets. Fig. 11 is a vertical longitudinal sectional diagram of the machine on the line *xx* of Fig. 12, illustrating the arrangement of the parts. Fig. 12 is a plan diagram.

Like letters of reference indicate like parts in each.

As heretofore constructed the heading-lever

was in form like a long arch turning on an inwardly-projecting center or journal at each end, the distance between which averaged about twenty-eight inches. The heading-die 55 was placed at the center of the arch, and power was communicated to the heading-lever from the short arm of the cutting-lever working vertically through a link against a projecting lug or horn on the back of the heading-lever. The 60 objection to this construction was that the strain of the work of heading the nail, coming on the heading-lever at the middle of its long arch, caused it to spring while upsetting the head, and thus prevented its delivering the 65 full strength of its blow at the instant it struck the nail-blank, and also produced strain on all parts of the lever and its bearings, which in time caused breakage. Another defect was that the power to operate the heading-lever 70 was applied to it against a long horn or projection, extending upward and backward from it over the short arm of the cutting-lever by means, as stated, of a link extending up from the cutting-lever and bearing against the said 75 horn. The distance between the end of the heading-die and the point on the projection to which the power was applied was comparatively great, and as the heading-lever in its movement described the arc of a circle struck 80 from its centers, the power was applied tangentially. The effect of the great distance between the end of the heading-die and the point where the power was applied thus tangentially caused another springing of the heading-lever, 85 which aided to produce the bad effects mentioned, and also frequently caused the breaking off of the horn or projection to which the power was applied.

Now, referring to the drawings, 1 represents 90 the bed, and 2 the heading-lever, which has a short transverse arm, 3, having bushing-chambers 4 in each end, in which the centers 5, upon which it vibrates, are placed. These centers 5 are placed inside of the bed, and the average 95 distance between them in the various sizes of my machine is five inches. It is apparent that there can be no spring in the heavy casting in this distance. The centers 5 of the heading-lever are situated almost directly below the 100 gripping-dies of the machine and directly under that side of the dies against which the head

of the nail is upset. The heading-die 6 is secured in a **V**-shaped recess, 7, in the heading-lever by means of a **U**-strap and set-screw 8, and the power is applied to the lever from the 5 short arm 9 of the cutting-lever 10 by means of a toggle, 11, working in bushed sockets 12. The toggle 11 bears against the levers in a vertical plane, which, if continued, would bisect the center of the heading-die 6. The toggle 11 is a single toggle, being a short arm placed between the extremity of the short arm of the cutting-lever and the outward extremity of the heading-lever, and having a bearing by ball-and-socket joint in each. When the machine 10 is not operating to head a nail, and the parts are in the position shown in Fig. 1, the position of the toggle-arm 11 is (as shown in Fig. 1) inclining downward and outward from the heading-lever to the cutting-lever. Now, 15 as the forward extremity or short arm of the cutting-lever rises, its extremity traverses the path of a circular arc, carrying with it one end of the toggle-arm 11, and in so doing turns it in its bearing in the gripping-lever not only, but 20 also brings the short toggle-arm 11 to a horizontal position in line with the axis of the heading-lever, and by so doing communicates the necessary movement, hereinafter described, to the heading-lever, of decreasing rapidity and 25 increasing force.

The movement of the toggle is such as to cause the heading-die to deliver a nearly direct blow or thrust on the blank. As during the forward motion the toggle approaches a 30 horizontal position, the power of the heading-lever increases, and the force changes from a blow to a crushing or compressive one, and effects not only the simple upsetting but also the compacting or compression of the end of the blank, producing an exceedingly strong, compact, and 35 polished head. The blow is also easier on the gripping-dies, being, as it were, cushioned, the movement of the die decreasing in velocity and increasing in power as it approaches the end 40 of its stroke, and completes the upsetting and compression of the head. The power being applied directly to the lever itself at a point comparatively near to the end of the heading-die, no spring of the lever in this particular occurs, 45 and the danger of breakage is reduced to a remote contingency.

As heretofore generally used, the gripping-lever was straight, extending in a right line across the bed of the machine, and the heading-lever extended up over it by the long arch 50 I have mentioned, passing under the cutting-lever which was arched upward at the right side of the cutting-dies, to permit its passage. I form my gripping-lever with a diagonal arch— 55 that is, an arch which extends both upward and backward. The purpose of this is to permit the placing of the short journaled heading-lever 2 in the position described, in the middle of the bed under the gripping-dies, so as to have 60 a direct and unyielding action on the blank. Another advantage of this construction is that

it stiffens and strengthens the gripping-lever and prevents the springing or shrinking under the blow of the heading-die, which is a defect in the prior construction referred to. Another advantage is that it is a more compact and economical construction, as it enables the levers to be placed nearer together, and thus saves room and reduces the necessary size and weight of the frame of the machine, and enables more machines to be placed in a given space. This is a very important point. 75

In the prior machine referred to the outer end of the heading-lever was journaled outside of the bed-plate. The stationary tools of the machine were mounted in a heavy solid stationary head, 46, on the bed-plate, and the heading-lever was parallel thereto, and when at the limit of its stroke came into close proximity to it. The result of this was that if a piece of scrap or other hard substance fell down between the stationary head and the heading-lever, the latter was almost invariably broken. The space between these two parts averaged about three-sixteenths of an inch, and 85 this was a fruitful cause of breakage. In my machine, the heading-lever being arranged and journaled within the bed and under the gripping-dies, this danger is completely obviated. 90

To prevent the nails as they fall from the dies from getting between the end of the transverse arm of the heading-lever and the bed-plate 1, I chamber out the bed-plate, as at 28, Fig. 11, and enter the short end of the transverse arm 3 into it, so that it shall act as a 100 shield and close the vertical space between the two parts effectually to the falling nail. The result of the nails getting in there might be to wedge the heading-lever, and by preventing its retraction cause the heading-die to be struck 105 by the moving knife.

I form a lug, 14, Figs. 3 and 11, on the back side of the transverse arm 3 of the heading-lever 2, which serves the double purpose of affording a bearing for the spring 15, which, 110 pressing down on the said lug, retracts the lever, and of striking the pin 16, which communicates a vibration to the nail-assorter. The spring 15 is attached to the bed at 90, Fig. 12, directly under the right-hand center, 5, of the 115 cutting-lever.

I form my cutting-lever 10 with a regular, or nearly regular, transverse arch between its centers 5, instead of the irregular arch at the right side of the moving knife of the prior construction referred to, and the result is that its rigidity is increased, the total length of the lever is shortened, and a saving of material effected. 120

The power to operate the cutting-lever, and through its short arm 9 the heading-lever, is 125 communicated from the power-shaft 20 to the long arm 17 of the cutting-lever by means of the crank-pin 13 and pitman 19, attached to wrist 18 on the long arm 17 of the cutting-lever.

In the prior machine referred to the journal-brasses were flush with the faces of the pit-

man, and the effect of this was that the entire side of the pitman-brass chambers 21 bore against the face of the crank-disk 22 and lever 17, producing great friction, wear, and loss of power. I make my brasses 23 with a flange, 24, at one end, and provide the chamber 21 with a recess, 25, at its inner end, of such depth, relatively to the thickness of the flange 24, that the brass shall project slightly from its chamber. I make the brass adjustable in the chamber by means of a set-screw 26, working through the side of the chamber against a steel strip or liner, 27. Then the brass 23 is the only part of the pitman that bears against the crank-disk 22 or the lever 17, and the friction is reduced to a minimum.

In the prior construction referred to the thrust of the link which communicates the power from the cutting-lever to the heading-lever is vertical, while the movement of the heading-lever is in the arc of a circle. The result is that the bushing of the right-hand center of the cutting-lever is worn oblong, which tends to disalign the cutting-lever, destroying the accuracy of the bearing of the right-hand center in its bushing, produces shackle motion, and thereby impairs the accuracy of the machine and increases the wear of its parts. In my machine the force of the toggle is nearly in a line with the right-hand center of the cutting-lever, instead of at right angles thereto, and this causes an even wear of the bushing and obviates the evils mentioned.

In said prior machine the link was not bushed, and rapid wear was the result. In my machine I provide the sockets 12 of the toggle 11 with bushings of any suitable material, (preferably phosphor-bronze,) which, being replaceable when worn, will save the wearing and consequent destruction of the lever-castings and reduce the friction of the machine.

Each lever is provided with female conical center bushings, 29, in which the conical centers 5 have their bearing. In the old machine these bushings were lubricated by an oil-hole bored transversely through the side of the lever and bushing into the center; but owing to the close contact of the center with its bush, little, if any, of the oil got in, and the lubrication was very imperfect. In a short time the wear resulting from the excessive friction would loosen the bush and permit it to turn in its chamber, and thereby close the oil-hole and shut off the supply of oil completely.

I construct the bushing-chamber 4 deeper than the bushing 29 and provide the bushing with several (preferably three) holes, 31, extending longitudinally from its smaller or inner end to and opening into the conical seat 32. I also make an oil-hole, 33, through the lever from the outside to and opening into the inner end of the bushing-chamber 4. Then when the bushing 29 is inserted into the chamber 4, an oil-chamber, 34, is formed between the inner ends of the bushing and its chamber, which oil-chamber is supplied through the oil-

hole 33. The oil passes from the oil-chamber 34, through the holes 31, to the conical end of the center 5 and lubricates it perfectly, thereby diminishing friction, heating, and wear. As the bearing of the center 5 is horizontal, the central hole, 29^x, would not suffice to furnish oil for lubrication, especially as the conical extremity of the center 5 has very little motion. To overcome this difficulty I make three ports, 31, to one side of the center of the bushing, through which the oil enters from the oil-space in rear of the bushing, which is left by the taper of the conical bushing, preventing its passing down to the bottom of the recess 80 made to receive it. The central hole, 29^x, is, therefore, not designed to serve as an oil-port, but is tapped with a screw-thread for the purpose of inserting a tool with a screw on its extremity to extract the bushing when it is desired to remove it.

In all prior machines having the fly or balance wheel fixed outside of the left-hand sustaining post or upright, 36, the weight of this wheel rotating in this position, added to the pull of the belt, which in American practice is invariably downward, tends to wear down the journal next to the fly-wheel faster than the opposite one. The disalignment of the shaft 20 thus produced caused a heating of the crank-pin 13 by impairing its parallel bearing in the pitman 19, and made the crank-disk 22 sometimes to rub against the pitman 19, necessitating such play in the bearings 23 as to greatly impair the efficiency of the machine. To overcome these difficulties I have located the fly-wheel 35 inside the support 36 and moved the rear arm, 37, of the gripping-lever more to the middle of the shaft 20 and in direct line with the work. By this arrangement I maintain a perfect alignment of the shaft, applying the momentum or impulse of the balance-wheel directly to the work instead of at one side of it, as heretofore.

In the prior machine the gripping-lever is retracted or caused to follow its operative cam by the aid of a spiral or leaf spring. In either case the spring exerts a pressure on the cam during the time of the gripping of the nail of from two hundred to five hundred pounds. This pressure or load is in addition to the legitimate load of the machine, and as the distance through which the lever is lifted will average about six inches and the number of times about two hundred and fifty per minute, the waste of power is considerable, and the machine is worn by the unnecessary friction. The spring does not retract the lever as promptly as the cam leaves it, which causes a pounding of the gripping-lever on the cam. This pounding and resultant vibration in time crystallize the iron and cause the shaft and lever to break. These various difficulties I have overcome in my machine by yoking the rear arm, 37, of the gripping-lever to the cam 38, as shown in Fig. 9, so that the gripping-lever, after being brought into action by its cam and re-

tained in that position while the nail-blank is being held by the grippers, is withdrawn by a sudden and positive motion, yet without jar, at the moment that the movable cutter has 5 severed the blank. The yoke 39 is a band of iron, steel, or other suitable material of sufficient rigidity to secure the proper definite action of the gripping-lever, although absolute rigidity is not necessary. The shape of this 10 cam-yoke is an irregular ellipsoidal curve of such contour that the cam begins to bear against the yoke at the moment (shown in Fig. 9) when the regularly-curved portion of the cam-face, which is farthest from the center of motion, 15 ceases to bear against the friction-plate, and immediately withdraws the gripping-lever. This contact of the cam-yoke and cam continues and operates to draw back the lever with a steady but rapid motion until the cam again commences 20 to bear against the friction-plate to raise the lever, and operates the same, whether the machine is run backward or forward.

I have been thus particular in describing this device, as I have been unable in any other way 25 to effect the retraction of the gripping-lever without the pounding action before referred to, which has hitherto been characteristic of nail-cutting machinery of the class referred to.

The friction-plate 40, which is embraced by 30 the cam-yoke 39 and bears on the cam 38, is of novel construction. It is placed in a slot or socket, 41, which, being longer than it is, permits of its adjustment by means of a set-screw, 42, and liners 43. This enables it to be 35 moved forward or backward in the slot 41 just as it may be desired to have it receive the stroke of the cam 38 sooner or later. It may, if desired, be made in two pieces, as shown at 44, Fig. 10, and then by inserting a liner, 43, 40 between the two pieces it can be caused to bear longer on the cam, and thus not leave it so soon. The free ends 45 of the yoke 39 are turned over at right angles on the upper part of the friction-plate, for the purpose of taking 45 up any play that may exist between the yoke and the cam, as shown in Fig. 9.

The stationary head or tool-box in the prior machine has the sides, in which the set-screws are located, very frequently broken off. This 50 was owing to a weakness in the casting which was caused by this part remaining fluid the longest, or being the last part of the casting to cool. The parts first or most quickly cooled possess the greatest strength. I secure 55 the rapid cooling of the stationary head 46 in my machine by locating a large core in this part, forming a large cavity, 30, Fig. 11, in the casting. This reduces the amount of metal and at the same time obtains greater tenacity, 60 solidity, and strength in this part than could be obtained if it was cast a solid mass, as heretofore. The breaking of this part often leads to an expense of from seventy-five dollars to two hundred dollars per machine, without counting 65 the loss of time, which is generally over a week.

In the prior machine various caps and other contrivances have been used to advance the centers of the levers; but these devices are cumbersome and inconvenient, necessitating several bolts and scrap, wood, or other packing to keep them in position. To overcome this difficulty I have constructed a cap, 47, held to the bed-plate with a collar-bolt, 48, and with a set-screw, 49, to advance the center. When 70 the center is to be withdrawn from the machine it is only necessary to slack the collar-bolt and the cap will swing completely out of the way. This device is complete, convenient, and effective. 75

The nipper-cam 82 works against duplicate friction-plates 83, Fig. 11, similar to the friction-plates 44, Fig. 10. These friction-plates 83 are placed in the end of the nipper rock-shaft 84 and bear against the cam 82. These 80 parts operate in the usual way.

In the prior construction referred to a small set-screw was inserted in the forehead of the cutting-lever opposite to the center of the gage-slot, for the purpose of limiting the forward 90 advance of the spring-gage or carrier-guide, which regulated the feed of the machine. In this position this set-screw was an obstruction and necessitated the location of the moving knife-screw over the corner of the knife instead 95 of over its center. I have overcome this difficulty by the construction shown in Fig. 6, in which the spring-gage 50 is pivoted in the gage-slot 51 by a screw-clamp, 52, in the cross-head 53. The point 54 of the gage 50 comes 100 just under the edge of the knife 55, which is always fed or set to the gage. The gage is held forward by the spring 56, which is inserted in the slot 51 back of it. The backward movement of the gage is limited by the 105 screw 57, and its forward movement by the screw 58, by the latter of which I am enabled to bring the point 54 of the gage flush with the front side of the knife 55. The gage may be adjusted vertically in the slot by means of 110 the screw-clamp 52. I prefer to use a lock-nut on the screw 58, to guard against accidental movement.

In the use of the machine the nail-plate 59 is fed against the point of the spring-gage, as 115 shown in Fig. 6, and this causes the gage to be pressed back until it comes in contact with the screw 57, which is properly adjusted to secure the required width of nail, and then the moving knife 55 descends and makes its cut. The cut blank is held by the spring-gage against the tools in the stationary head 46 (at the point 60 in Fig. 11) as the knife 55 pushes it down into the gripping-dies, and for this reason the gage is also called a "carrier-guide." 120 The moving knife 55 is adjusted in the head by means of the adjusting-screw 61.

Great difficulty has heretofore been experienced in making effective attachments of self-feeding devices to the former construction of 125 nail-machines. I have constructed my machine with special reference to this feature.

When it is desired to make such an attachment I place an oscillating arm or rock-shaft, 62, beneath the bed-plate 1 and fulcrum it in suitable journals in lugs 63, cast on the bed-plate near the center of the machine. The rear end of the rock-shaft 62 is connected by a pitman, 64, or other suitable device, to a crank-shaft, 65, rotating in journals 66, situated in the base of the main-shaft supports 36. The shaft 65 receives its motion from a toothed gear-wheel, 67, placed on the main shaft 20, between the belt-pulley 68 and the post or upright 36. It has a gear-wheel, 69, of double the diameter and number of teeth of the gear-wheel 67, so that the crank-shaft 65, which actuates the self-feeder rock-shaft, shall only make one-half the number of revolutions that the main shaft does. The forward end of the rock-shaft 62 is to be connected by a ball-and-socket or other suitable joint, 70, to a pitman, 71, or other suitable connection to the self-feeding device.

The purpose of my above construction is to furnish a simple, effective, and reliable power attachment for the feeder. The feeder requires to be turned over in order to turn the nail-plate 59 one-half a revolution at every stroke of the knife 55, and it is caused to be so turned on the upstroke of the pitman 71, and then turned back again at the downstroke. Thus one oscillation of the rock-shaft 62 supplies the proper power to turn the nail-plate over and back, and enable it to be properly presented to the knife 55 at two consecutive strokes of said knife, and for this reason the crank-shaft 65 is required to make only one revolution while the main shaft 20 is making two revolutions.

I do not represent any self-feeding device in this application, but merely show a power attachment which will enable any one of a number of known self-feeding devices to be applied to the machine.

The journals of the self-feeder crank-shaft 66 are held down by a conical-pointed binding-screw, 82, (see Fig. 11,) placed in the standards or housing, and bearing on the upper brass, 83, thereby doing away with journal-caps. In case the screw 82 is put in horizontally, the top of the brass 83 should be inclined or beveled to produce the same result. The said screw may be inserted vertically from below and bear on the lower brass, but in all cases it passes through the housings.

I have also devised improved means of attaching the nail-separator and its agitating device to the machine. I attach by a suitable bolt, 72, to the under side of the machine a bracket, 73, having a suitable grooved face, in which, by means of the clamp 74, I fasten the supporting-rods 75 of the separator 76. The agitator 77 is supported by another bracket, 78, in which it is loosely pivoted, being fastened by a set-screw, 79. The other end rests loosely in the angle-socket 80 on the rear end of the vibrating rod of the separator. The agi-

tator receives its motion through the vertical rod 16, which, projecting into the path of the heading-lever 2, is struck by the under side of the lug 14, Fig. 11, and communicates the jar so received to the separator. The rod 16 is fastened to the rod 77 by a right-angled joint, 81, which is adjustable and can be set in any position on the rod 77. This construction of the attachment devices is more convenient and out of the way than that heretofore used, and renders the operation of the separator more perfect, as it secures to it the full benefit of the jar of the nail-machine.

What I claim as my invention, and desire to secure by Letters Patent, is the following-described improvements in that class of cut-nail machines in which the cutting-lever actuates the heading-lever, viz:

1. The arrangement of a diagonally-arched gripping-lever, with a heading-lever pivoted centrally below the gripping-dies, so as to operate within the diagonal arch of the gripping-lever, substantially as described, for the purpose of securing rigidity and certainty of action of the heading-lever and greater compactness of construction.

2. The single toggle-arm 11, seated by ball-and-socket joints in and between the extremity of the short arm of the cutting-lever and the extremity of the heading-lever at an angle to the axis of the latter, so that when the short arm of the former is raised it communicates a rapidly-decreasing movement to the heading-lever by bringing the toggle-arm in line with the axis of the heading-lever, substantially as described.

3. The combination of a heading-lever having a short transverse arm, a toggle for communicating a forward movement to said lever, a lug on the transverse arm of the lever, and a spring bearing on said lug for retracting the lever, substantially as described.

4. The combination, with the arm of the gripping lever and cam for operating the same, of the divided bearing composed of the cam-friction plates adjustable to and from each other to vary the length of time of contact between the cam and gripping-lever, substantially as specified.

5. The combination of the rear arm of the gripping-lever and the cam 38 on the main shaft with an ellipsoidal cam-yoke, constructed substantially as shown, for the purpose of communicating the peculiar required intermittent motion to the lever, substantially as described.

6. In the combination of a moving cutter having spring-gage pivoted in its rear, an adjusting-screw to the cutter, and a stop device to limit the forward movement of the gage, the arrangement of the stop device back of the gage so as to permit of the location of the adjusting-screw centrally to the cutter, substantially as described.

7. The arrangement, in a cut-nail machine, of a rock-shaft pivoted below the bed for communicating power to a self-feeding device, and

operated by power from the main shaft through the medium of shafting and gearing, substantially as and for the purpose described.

8. In combination with a cut-nail machine, 5 the bracket 73, for sustaining and connecting a nail-separating device, substantially as described.

9. In combination with a cut-nail machine, the bracket 78, for sustaining the agitator of

the nail-separating device, substantially as de- 10 scribed.

In testimony whereof I have hereunto set my hand.

JOHN COYNE.
